FRANK V. BURTON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ATTACHMENT-PLUG RECEPTACLE.

1,365,152.

Specification of Letters Patent. Patented Jan. 11, 1921.

Application filed January 15, 1916, Serial No. 72,319. Renewed December 9, 1920. Serial No. 429,584.

To all whom it may concern:

Be it known that I, FRANK V. BURTON, a citizen of the United States of America, and residing at Bridgeport, in the county of 5 Fairfield and State of Connecticut, have invented a certain new and Improved Attachment-Plug Receptacle, of which the following is a specification.

My invention relates to attachment plug 10 receptacles and particularly to a receptacle adapted to coöperate with attachment plugs which have their jacks in different relative arrangements. The object of my invention is to provide a receptacle in which the terminal means comprises contacts of opposite 15 polarity and the same potential so arranged within the area defined by a single coöperating plug, that within this prescribed area means are afforded to receive jacks of different relative arrangement.

In the accompanying drawing which shows a single embodiment of my invention,

Figure 1 is a cross section through an 25 outlet box showing the present receptacle mounted therein;

Fig. 2 is a plan of the receptacle alone;

Fig. 3 is an inverted plan of the same with the terminal means of one polarity re- 30 moved;

Fig. 4 is a vertical section on the line 4—4, Fig. 2; and

Fig. 5 is a perspective of one of the terminals.

For simplicity of illustration and explanation, my invention has been shown in the accompanying drawing in a receptacle of the flush type, but it is to be understood that the invention may be applied to receptacles 35 of any desired type such as current taps associated with sockets, switches or other electric fittings to which the invention is applicable. Referring to Fig. 1, an outlet box 10 of usual construction is here illustrated provided with inwardly-extending tapped ears 11. The receptacle body 12 of insulating material of any suitable sort carries, at its opposite ends, lugs 13 through which pass the screws 14 by means of which the receptacle is secured to the ears 11 of the outlet box. These lugs 13 are tapped at 15 to receive the screws 16 which hold the face plate 17 in position above the outlet box. This cover plate is centrally apertured to receive 55 a circular boss 18 on the upper face of the

receptacle which fits substantially flush with the face plate and positions the latter with relation to the receptacle.

On diagonally opposite corners of the receptacle are depressed ledges 19 on which 60 are seated the wire terminals 20 and 21, the securing screws 22 and 23 for which pierce the base 12 and connect the terminals to straps 24 and 25 let into the lower face of the base. Additional securing screws 26 65 and 27 may be provided to mechanically secure these straps in position on the base.

Within the area of the boss 18 the receptacle is pierced by four holes 28, 29, 30 and 70 31 to accommodate the terminal contacts and to form guides for the jacks of a coöperating attachment plug. These terminals, as here shown, comprise for each pole of the receptacle, a pair of blades 32, 33 and 34, 35. One pair of terminal blades is mounted upon 75 strap 24, and the other pair upon strap 25. Preferably these blades are formed of spring sheet metal, and each is provided with an offset base secured to its appropriate strap by a rivet 36. The arrangement of 80 the blades and their corresponding slots in the receptacle is such that they afford pairs of receiving terminals of opposite polarity, one pair, viz. 32 and 34, lying substantially in tandem, while the other pair, viz. 33 and 85 35 lie substantially in parallel. The receiving terminal means afforded by the present receptacle, within the area of a single coöperating attachment plug, thus constitutes pairs of receiving contacts, both pairs being 90 of the same potential, adapted to receive the jacks of a coöperating plug, whether the jacks of the latter are arranged in parallel to engage the terminals 33 and 35, or in tandem to engage the terminals 32 and 34. 95

It is obvious that this construction is of great commercial utility, since both types of plugs are common upon the market. Moreover, it is a common practice for manufacturers of portable, electrically driven apparatus of various types utilized for domestic or other service to supply this apparatus with the leading-in cable and an attachment plug, but without a receptacle. Since some manufacturers adopt a plug with parallel 100 jacks, and other manufacturers adopt one with tandem jacks, it necessitates for the user either a duplication of independent receptacles, or the substitution of a different type of plug for that purchased with the 110

apparatus, in order that the latter may be utilized with that special type of receptacle which the user may happen to have already installed. By the novel arrangement of the 5 receiving terminals of the present receptacle, the latter is rendered substantially universal in its utility,—a feature of economy and convenience which will be readily recognized.

- 10 In the particular embodiment of the invention here shown, the receptacle is of a construction particularly economical, since the body 12 constitutes but a single block of insulation. The straps 24 and 25 may be 15 struck from sheet metal and the contacts 32 to 35 are readily secured thereon by riveting, while the straps and their associated contacts may be assembled upon the receptacle body by unskilled labor at a very low cost.
- 20 The receptacle may therefore be marketed at a cost less than that now prevalent for receptacles of ordinary type, while at the same time the present article has a greatly enhanced utility and convenience.
- 25 As above stated, I do not limit my invention to flush receptacles of the type shown, since it may be applied to receptacles of any type with which attachment plugs are intended to coöperate. The precise details of 30 construction, even in the type shown, may be variously modified without departing from what I claim as my invention.

I claim as my invention:—

1. An attachment plug receptacle comprising an insulating block pierced to afford 35 guideways for the jacks of a coöperating attachment plug, straps of opposite polarity mounted on the inner face of said block and receiving terminal means mounted on each of said straps and entering the guideways 40 in the block, said terminals being arranged to coöperate with an attachment plug having its jack lying either substantially in tandem or substantially in parallel.

2. An attachment plug receptacle comprising an insulating block pierced within the area defined by a coöperating attachment plug, to afford guideways for the jacks of a coöperating attachment plug, straps of 45 opposite polarity mounted on the inner face 50 of said block and receiving terminal means mounted on each of said straps and entering the guideways in the block, said terminals being arranged to coöperate with an attachment plug having its jacks lying either substantially 55 in tandem or substantially in parallel.

In testimony whereof I have signed my name to this specification in the presence of two subscribing witnesses.

FRANK V. BURTON.
